UNITED STATES PATENT OFFICE.

ADAM E. CHODZKO, OF SAN FRANCISCO, CALIFORNIA.

CONTINUOUS COMPRESSION OF FLUIDS.

SPECIFICATION forming part of Letters Patent No. 690,100, dated December 31, 1901.

Application filed September 4, 1900. Serial No. 28,925. (No model.)

To all whom it may concern:

Be it known that I, ADAM E. CHODZKO, a citizen of the United States, residing in the city and county of San Francisco, State of California, have invented an Improvement in Centrifugal Machines; and I hereby declare the following to be a full, clear, and exact description of the same.

The present invention applies to improvements in a centrifugal machine, whereby pressure is produced in fluids, either liquid or gaseous, in a continuous way instead of using, as done universally nowadays, the reciprocating action of a piston moving back and forth into a cylinder.

The invention consists of the parts and the constructions and combinations of parts hereinabove described and claimed.

Referring to Figure 1, A is a vessel in the form of a solid of revolution, no specific shape being here represented, said vessel having a central opening B and being also centrally attached to a shaft or spindle C, perpendicular to the plane of rotation, and by means of which a gyratory motion can be imparted to the vessel. Let now the shaft C be set in motion and a fluid be introduced into the vessel through the central opening. This fluid will be projected by the vanes V against the internal periphery of the vessel and will remain at that point in a state of pressure due to the centrifugal action. It would, however, be of no use unless collected for subsequent utilization, and for this purpose a stationary pipe D, which penetrates the vessel through its central opening B, is secured with the plane of its open end E turned against the direction of rotation, as shown by the arrow. Calculation and actual experiment concur in showing that the fluid is thus scooped out by the stationary pipe D, which conveys it to a closed receiver at a pressure double what it would be owing to the tangential velocity alone, which now combines with the centrifugal force 45 to produce this pressure.

If a continuous supply of fluid is allowed to enter the vessel at its center and is subsequently withdrawn, as described, at its periphery, a continuous flow of compressed fluid 50 will be established with no other mechanical action than imparting to the vessel a conveniently high rotary speed.

One object of the present invention is to devise practical means whereby the principle involved is extended to the generation of high 55 pressure, either in water or other liquids or in atmospheric air or other gases.

Analytical investigation of the subject leads to well defined rules governing the operation of such machines; but the requisites differ 60 so widely, according to whether gases or liquids are concerned, that a separate description of the machines used in both instances is necessary.

Fig. 1 is a diagrammatic view illustrating 65 the invention. Fig. 2 is a longitudinal section of a horizontal form of apparatus. Fig. 3 is an end elevation. Fig. 4 is one-half transverse section on the line *x* *x* and one-half transverse section on the line *y* *y* of Fig. 2. 70 Fig. 5 is a plan of an air-compressing plant. Fig. 6 is a vertical section on the line *z* *z* of Fig. 5. Fig. 7 is a vertical section showing a modified form of construction of the same. Fig. 8 is a half-horizontal section on the line 75 *u* *u* and a half-plan on the line *v* *v*, Fig. 7.

The machine shown under these numbers is illustrative of the process, but subject to modifications of detail. For instance, the spindle could be set vertically instead of horizontally, and the machine could be operated directly by an electric or other motor instead of through an intermediate connection, as shown, &c. It must be understood that such modifications and others of a similar nature 85 would not affect the novelty of the proposed method for raising the pressure in liquids.

The revolving vessel A, mounted on the spindle C, receives a rapid rotary motion from a belt actuating the pulley 2. Water is supplied to the chamber 3, from which it enters the central trunnion 4 of the revolving vessel. This vessel is formed of two parts 5 and 6, jointed at 7 and firmly secured together by a shoulder and a nut 8, carried by the spindle. 95 The part 5, which forms the outer shell, is cast with the trunnion 4, with a portion of hub, and with a convenient (and preferably even) number of vanes V V, whose function it is to divert the water arriving at the center toward the equatorial diameter of the shell. The second part 6 is cast with the remaining portion of the hub and with vanes V' V', which when parts 5 and 6 are secured to-

gether are uninterrupted extensions of vanes V. The vanes V V' form, therefore, continuous passages from the center of shell 5 to its periphery, where short radial projections 9 5 help in entraining the ring of water under pressure in the whirling motion of the shell. Two collectors or scoops 10 are set as shown and slice off the water at the periphery of the revolving shell, whence it passes through the 10 pipes 12 into the main 13, leading to any pressure-receptacle. Automatic means must of course be provided to proportion the supply of water at 3 with the amount scooped out and also for shutting off the supply should 15 the machine stop. Some mechanism acting like a centrifugal governor would accomplish this object. Such a governor is illustrated at 25 and acts through a lever 26, a connecting-rod 27, and a crank-arm 28, which is fixed to 20 the stem of a butterfly or other equivalent valve controlling the supply-passage. The scoops can also be made to swing around the center of their respective discharge-pipes, so as to slice off more or less water without 25 altering the speed and the pressure. The adjustment of these scoops may be effected in various ways, one of which is shown in Fig. 3, in which the scoops and their discharge-pipes being turnable so as to swing 30 the mouths of the scoops to or from the center these movements are effected by means of rocker-arms 29, connected with the sections which carry the scoops. These arms are connected to move in unison by a rod or 35 link 30, and a lever 31 serves to operate the two. The front part of the revolving vessel through which the stationary scoops penetrate the shell is therefore open, as when in motion there should be no tendency of the 40 water to spilling toward the center. The main advantage of this arrangement is that the frictional resistance due to the liquid under pressure is exerted only at the tips of the scoops.

45 The conditions governing the compression of gases differ from those concerning the liquids on two principal grounds: First, the speeds of rotation are considerably higher, and, second, even at the practical limit of velocity a gas could not be raised in one machine from atmospheric to a much higher pressure. Hence the necessity of using machines in series, the compression being effected in successive stages as the gas passes from one machine to the next.

55 For the sake of argument, and also as corresponding to the most extensive application, atmospheric air will be referred to, although the following details would apply to other 60 gases as well.

First. A high speed of rotation has two immediate consequences: (a) The shell must be constructed to resist bursting under centrifugal force. This is a vital point in this class 65 of machinery, and well-defined relations exist between the shape of the revolving shell, the material of which it is made, and the

speed of rotation. The homogeneity of the material of which the shell is made is here an important element, as an uneven repartition of the components of an alloy, if their specific gravities are very different, might contribute to throw the machine out of balance. Special brands of tough forged steel are used in the construction of steam-turbines, and the same would answer for the side plates of the revolving shell. The rim should be reinforced at its periphery by winding around it some small steel wire of high tensile strength, which would also possess the advantage of homogeneity. With certain designs of shells, however, forged-steel side plates would be difficult of construction and very expensive. It is therefore proposed in such cases to form these 85 plates of a cast core, reinforced by winding over it a small steel wire 14 of much higher tenacity than could be obtained from forged or cast metal of any description. (b) Another effect of a high speed manifests itself 90 by the difficulty arising in a satisfactory centering of the revolving shell.

Passing now to the description of a fluid-compressor working on the continuous principle, Figs. 5 and 6 illustrate a set of three 95 machines in series, each shell discharging into a closed casing 21, from which the fluid is drawn and compressed, then discharged through the top pipe into an intercooler 22, and then led to the casing of the next machine until the air discharged by the last one 100 in the series is at a convenient pressure.

On the above-named figures the mechanism which sets the driving-rollers in gear actuates a double-beat discharge-valve 23, (shown 105 on top of the casing,) and whose object it is to intercept the communication between the machines when they are stopped, so as to avoid wasting the compressed air contained in the pipes and casings. Automatic check-valves would accomplish the same object, and the disposition here represented is simply illustrative of one positive way of isolating the machines when stopping. The air-pressure may be varied with the speed of rotation of all the machines or of any particular machine in the series or else by maintaining the speed and adding more machines to or withdrawing some machines from the series.

110 It must be understood that the air-compressing plant illustrated in Figs. 5 and 6 represents one possible arrangement, but that other mechanical dispositions of machines built and operated on the same principle can be devised and are intended to be covered by this specification. This apparatus also acts as a self-regulator. When the pressure reaches a given amount, the air ceases to pass 115 into the receiver and is therefore not drawn into the apparatus again until pressure in receiver is reduced and the speed of engine remains constant.

120 Having thus described my invention, what

I claim as new, and desire to secure by Letters Patent, is—

1. In a centrifugal machine, a revoluble shell open upon one end and having a central 5 annular inlet, vanes revoluble with the shell and acting to direct the fluid toward the periphery, and fixed collecting-scoops.
2. In a centrifugal machine, a revoluble shell open upon one end having an inlet-passage, vanes or guides by which the fluid drawn in by the revolution is directed into the periphery of the shell, scoops or collectors extending into the shell through the end and a discharge-passage connecting therewith.
- 15 3. In a centrifugal machine, a revolving shell open upon one end having an inlet, vanes or guides turnable with the shell by which the fluid is directed to the periphery of the latter, stationary scoops or collectors 20 entering the shell through the end having tips entering the revolving ring of fluid at the periphery of the shell and slicing off a portion equal to the area of the entering tip.
4. In a centrifugal machine, a revoluble 25 shell open upon one end having a fluid-inlet at the opposite end and increasing in diameter from the inlet end, blades or guides by which the fluid is directed from the inlet into the larger periphery of the shell, fixed scoops 30 entering the open end and having collecting-tips entering the revolving ring of fluid so as to slice it off and convey it out of the shell, said scoops being adjustable to increase or diminish the amount collected by them.
- 35 5. In a centrifugal machine, a revoluble conical shell open at one end and having an inlet at the opposite end, vanes or guides by which the fluid is directed into the periphery of the shell, and caused to revolve in unison 40 therewith, a series of fixed scoops or collectors, the tips of which enter the revolving ring of fluid and discharge-pipes entering the open end of the shell, with which pipes the scoops are connected.
- 45 6. In a centrifugal machine, a conical revolving shell having an opening at the larger end, means for supplying fluid to the opposite end, and vanes or guides by which said fluid is directed into the periphery of the shell and 50 caused to revolve in unison therewith, conducting-pipes leading into the open end of the shell, scoops or collectors having one end adjustably connected with the discharge-pipe, and the outer ends or tips entering the revolving 55 ring of fluid at the periphery of the shell whereby portions of the fluid are continually sliced off and delivered through the discharge-pipes.
7. In a centrifugal machine, a revolving 60 shell having an open end, means for supplying fluid to the opposite end, and vanes or guides by which said fluid is directed into the periphery of the shell and caused to revolve in unison therewith, conducting-pipes 65 leading into the open end of the shell, scoops or collectors having one end adjustably connected with the discharge-pipe, and the outer ends or tips entering the revolving ring of fluid at the periphery of the shell, whereby portions of the fluid are continually sliced off and delivered through the discharge-pipes.
8. In a centrifugal machine, a revolving shell and a pipe for supplying a fluid into the interior of said shell, scoops projecting into said interior to slice off and collect the fluid therein, discharge-pipes with which said scoops are connected, and means whereby the 80 scoops are adjusted in unison with the adjustment of the supply-pipe opening.
9. In a centrifugal machine, a revolving shell, a valve-controlled admission-pipe thereto, and scoops whereby the fluid carried by the shell is collected and withdrawn, said scoops being adjustable to increase or diminish the amount collected, and a connection between the scoops and the valve controlling the admission-pipe, whereby the opening of 90 the pipe is proportioned to the amount carried away by the scoops.
10. In a centrifugal machine for fluid-pressure, a revolving shell and movable collecting and discharge scoops, a valve-controlled 95 supply-pipe, through which fluid is delivered into the shell, and an automatic connection between the scoops and the supply-controlling valve whereby an equality is secured between the amount of fluid entering the machine and the amount withdrawn therefrom.
11. The combination in a centrifugal fluid-pressure apparatus, of a plurality of revoluble shells with central annular inlets, vanes revoluble with the shells, collecting-scoops 105 projecting into the fluid within the shell, pipes connected with the scoops to receive the collected fluid and convey it therefrom, and receivers into which they discharge and from which the succeeding shell draws its supply. 110
12. The combination in a fluid-pressure apparatus of a plurality of revoluble shells with central annular inlets and interior directing-vanes, collecting-scoops projecting into the fluid within the shell, pipes connected with 115 the scoops to conduct the collected fluid, receivers into which said pipes discharge, and from which the succeeding shell draws its supply, and check-valves to prevent the return of fluid from the receivers to the shells. 120
13. A fluid-compressor consisting of a plurality of centrifugal revolving shells open upon one side and having a central inlet, vanes revoluble with the shells, fixed collecting-scoops, admission and discharge passages so disposed that the fluid compressed in one machine of the series is delivered into the casing of the next and check-valves by which a return through the apparatus is prevented. 125
14. A fluid-compressor consisting of a plurality of centrifugal revolving shells open upon one side and having a central inlet, vanes revoluble with the shells and acting to 130

direct the fluid toward the periphery, admission and discharge passages and fixed collecting-scoops so disposed that the fluid compressed in one machine is delivered into the 5 casing of the succeeding, check-valves to prevent the return of fluid discharged from either casing, and cooling-chambers interposed between each of the machines of the series through which the fluid is caused to 10 pass.

15. In a high-speed centrifugal machine, a revoluble shell open upon one side and having inlet and discharge passages, vanes rev-

oluble with the shell and acting to direct the fluid toward the periphery, fixed scoops 15 or collectors, a shaft through which motion is communicated to the shell, and yielding bearings whereby the shell has a freedom of motion about its geometrical center.

In witness whereof I have hereunto set my 20 hand.

ADAM E. CHODZKO.
